UNITED STATES PATENT OFFICE.

WILLIAM L. BARRELL, OF LAWRENCE, MASSACHUSETTS.

WEFT-REPLENISHING LOOM AND MAGAZINE THEREFOR.

1,321,275.

Specification of Letters Patent. Patented Nov. 11, 1919.

Application filed January 3, 1916. Serial No. 69,793.

To all whom it may concern:

Be it known that I, WILLIAM L. BARRELL, a citizen of the United States, residing at Lawrence, in the county of Essex and State 5 of Massachusetts, have invented new and useful Improvements in Weft-Replenishing Looms and Magazines Therefor, of which the following is a specification.

In my copending application, Serial No. 10 5,221, filed January 30, 1915, I have shown and described a loom in which two shuttles are interchanged whenever new filling is required, one of the shuttles being held in reserve away from the shuttle box while the 15 other shuttle is operated. I have also shown shuttle-loading mechanism, a magazine for weft carriers, and a chute arranged to conduct the weft carriers from the magazine into register with the shuttle-loading mechanism. In that case the travel of the weft 20 carriers from the magazine to the shuttle-loading mechanism is due solely to gravity.

The object of my present invention is to provide a loom of the character stated with 25 a detachable and portable magazine and with transferring means arranged to transfer the weft carriers positively from the magazine into register with the shuttle-loading mechanism. Since the transferring 30 means acts positively to carry the weft carriers, the latter are not dependent upon the force of gravity for their transfer, and the possibility of failure of operation due to sticking or disarrangement of the weft carriers is minimized if not wholly obviated.

Of the accompanying drawings, which illustrate one form in which the present invention may be embodied:

Figure 1 represents an elevation of the 40 change end of a loom embodying some of the characteristic features of the so-called Stafford loom, such loom in the present instance being provided with a magazine for weft carriers and with my improved mechanism for transferring the weft carriers from the magazine into register with the shuttle-loading mechanism.

Fig. 2 represents a top plan view, partly broken out and shortened, of the transferring means mentioned in connection with Fig. 1.

Fig. 3 represents a vertical section through the structure intersected by line 3-3 of Fig. 2. See also line 3-3 of Fig. 12.

Fig. 4 represents a longitudinal sectional

view of a weft-end carrier. Each weft carrier includes the usual bobbin and a detachable device like that shown by Fig. 4.

Fig. 5 represents an end elevation of the weft-end carrier shown by Fig. 4. 60

Fig. 6 represents a longitudinal vertical section through the transferring mechanism, as indicated by line 6-6 of Fig. 2.

Fig. 7 represents a top plan view, partly in section, of the device which forces a bobbin into a shuttle. 65

Fig. 8 represents an end elevation, similar to Fig. 1, including the support on which the shuttles rest while being loaded, and a portion of the transferring mechanism and 70 a device arranged to detach the weft-end carriers from the bobbins.

Fig. 9 represents a longitudinal vertical section through the transferring mechanism, as indicated by line 9-9 of Fig. 2. 75

Fig. 10 represents a front elevation of the assemblage shown by Fig. 8.

Fig. 11 represents a rear elevation of the assemblage shown by Figs. 8 and 10. See line 11-11 of Fig. 9. 80

Fig. 12 represents an elevation, partly in section and partly broken out and shortened, of the transferring mechanism, the direction of view being indicated by line 12-12 of Fig. 2. 85

Fig. 13 represents a top plan view including the support on which the shuttle rests for loading, a loaded shuttle thereon, and the same shuttle represented by dotted lines at an intermediate position on its way from 90 the said support to the shuttle box of the lay.

The same reference characters indicate the same parts wherever they occur.

Although the loom *per se* does not constitute the essence of the present invention, I 95 have included enough of a loom in Fig. 1 to show the relation of the magazine and transferring mechanism, but it will not be necessary to describe the loom nor the mechanism by which the shuttles are interchanged, because the latter elements are substantially as shown and described in the said copending application, Serial No. 5,221. It will be sufficient for present purposes to state that the reserve shuttle indicated at *x* is in position to be charged by the shuttle-loading mechanism hereinafter described, and that the shuttle indicated at *x'* is in operative position in the shuttle box of the lay *b*. The reserve shuttle *x* rests upon a fixed support 100 105 110

15. This support is affixed to and projects laterally from the breast-beam indicated at 16 in Fig. 11.

The shuttle-loading mechanism is substantially like the shuttle-loading mechanism of the well-known Northrop loom, and includes a loading arm or hammer 17. This arm is carried by a hub 18 (Fig. 7) and is normally raised by a helical torsion spring 19. The hub is mounted upon a stationary rod or stud 20 about which it may turn. An arm 21 carried by the hub 18 is pivotally connected by a stud 22 with the forward end of the bar 23. The rear end of this bar is movable up and down to and from register with a striker 24 carried by the lay. As shown by Fig. 1 the bar 23 is in its lowest position, this being its normal position, and it is raised only when the shuttle-changing mechanism is brought into action. Although Fig. 1 includes mechanism arranged to move the bar 23 into register with the striker 24, it will not be necessary to describe such mechanism excepting to state that during the shuttle-changing operation the rear end of the bar 23 is moved into register with the striker 24 and that upon the first beating-up motion of the lay following a change of shuttles the striker engages the bar 23 and moves the latter toward the front of the loom, also that upon the first backward movement of the lay the bar 23 drops from register with the striker and remains in the position shown by Fig. 1 until the next operation of the shuttle-changing mechanism. The forward motion of the bar 23 causes the loader 17 to descend and force the bobbin indicated at *a* into the reserve shuttle *x*. It may be stated that the bobbins and shuttles are substantially like those used in the Northrop loom hereinbefore mentioned. The usual three wire rings on the base end of the bobbin are shown in Figs. 7 and 11, but the bobbins are represented conventionally in this respect in the other figures, for the sake of simplicity.

The bobbins are carried successively into register with the shuttle-loading mechanism by transferring mechanism which includes a rotary carrier 25 and an endless link belt carrier or conveyer. The carrier 25 is in most respects the same as the well-known rotary magazine of the Northrop loom, but in this case it does not have any spring clamps for holding the bobbins. As shown by Figs. 2, 10 and 11, the rotary carrier comprises two co-operative disks 26, 27,—disk 26 being provided with sockets 26' adapted to receive the large ends *a'* of the bobbins, and disk 27 being provided with sockets 27' arranged to receive the bobbins as shown by Figs. 10 and 11. The disks 26 and 27 are, to all intents and purposes, a unit, and are provided with hub portions 28 and 29 which are affixed to each other. This carrier is

mounted upon a stationary rod or axle 30. Disk 26 is provided with ratchet teeth 31 by which it is rotated step by step to move the bobbins successively into register with the loader 17. For this purpose the loader is provided with a pawl 32 arranged to impart rotary movement to the carrier as the loader rises after forcing a full bobbin into the shuttle, all according to the well-known operation of the loading mechanism of the Northrop loom.

The bobbins are retained in the sockets 26', 27' by a fixed curved plate 33 until they reach a position in register with the loader. In this position they are supported by a pair of spring-pressed latches 34 (Figs. 6, 10 and 11). These latches are pivotally mounted upon a rod 35 and their free ends are normally raised by helical torsion springs 36. These latches are so disposed as to be displaced by the bobbin at *a* as the said bobbin is being forced downwardly toward the shuttle *x*, and as soon as the bobbin has passed the free end of the latches the latter are returned to their normal position by the springs, where they are adapted to support the next bobbin. The plate 33 is omitted from Fig. 11 to expose other elements to view.

Each bobbin, upon being placed in the magazine, is provided with a weft-end carrier of the form shown by Figs. 4 and 5. This carrier consists of a single piece *c* of sheet metal drawn to a cup shape and provided with a flange or rim *c'*. The body of this device is tapered, and is split by a kerf *c*², and the portions separated from each other by the kerf are adapted to grip the small end of a bobbin when the device is placed on the bobbin as shown by Fig. 3. The kerf *c*³ is formed in the rim *c'* to receive the weft end, and the latter may be fastened to the member *c* by placing it in the kerf *c*³, winding it one or more times around the body of the member *c*, and tying the end or laying it again in the kerf *c*³. The weft-end carrier remains on the bobbin until the latter reaches the position indicated at *a* in Figs. 1 and 6, but before the bobbin is depressed by the loader 17 the weft-end carrier is detached from it automatically by mechanism hereinafter described.

The conveyer comprises a pair of endless series of links 37 and 38 pivotally connected with each other by pivot rods 39. Each pivot rod extends through two contiguous links 37 and through two contiguous links 38, and the ends of the rods project laterally beyond the conveyer and are provided with anti-friction rolls 40. These rolls travel in grooves 41, 41 formed in fixed supports 42 and 43, and roll on the bottoms of the grooves. The conveyer is driven by sprocket wheels 44, 44 and passes over idle sprocket wheels 45, 45. These

sprocket wheels are formed with notches 46 (Fig. 6) and are arranged to receive the anti-friction rolls 40 in said notches. Sprocket wheels 44 are affixed upon a shaft 5. 47. This shaft is provided with a spur gear 48 which is driven by a spur gear 49 carried by the rotary disk 26. The conveyer thus receives its motion from the rotary carrier, the spring 19 (Fig. 7) being 10 the prime mover.

Each link 37 is formed with a socket 50, and each link 38 is formed with a socket 51. Each weft-carrier is carried by a link 37 and a link 38, the socket 50 being adapted to receive the large end *a'* of the bobbin and the socket 51 being adapted to receive the weft-end carrier *c*, as shown by Figs. 2 and 3. The spacing of the sockets of the conveyer is equal to the spacing of 20 the sockets 26', 27' of the rotary carrier, and the sockets of the one register successively with the sockets of the other to transfer the bobbins from the conveyer to the rotary carrier. (See Figs. 6 and 9). As the 25 links of the conveyer pass around the sprocket wheels 44 they are tipped so as to discharge the bobbins by gravity into the sockets of the rotary carrier, and the bobbins are retained in the latter sockets by the 30 curved plate 33 hereinbefore mentioned.

The magazine for the weft carriers is indicated as a whole at 52 in Figs. 1, 3 and 12. This magazine is arranged to rest upon the supports 42 and 43, but is detachable from 35 said supports so that it may be taken away from the loom for recharging. The body of the magazine is a substantially rectangular box, and its lower edges are adapted to enter rabbeted portions 53, 53 of the said 40 supports to be registered relatively to the conveyer. The magazine is divided by partitions 54 into a series of compartments, and the weft carriers are placed one upon another in stacks in the several compartments. 45 When the magazine is in the desired position upon the supports 42 and 43 the several stacks of weft carriers register respectively with the sockets of the conveyer. In other words, the centers of the weft carriers 50 in the magazine are in vertical alinement with the centers of the sockets of the conveyer. Consequently when the weft carriers are discharged from the magazine they drop 55 without any deflection from a vertical plane into the sockets with which they are in register.

The discharge of the weft carriers from the magazine is controlled automatically by means hereinafter described, whereby those 60 of the rear compartment are discharged first, then those in the second compartment from the rear, and so on until those in the front compartment are discharged. The several stacks of weft carriers are initially 65 supported by stops 55. Each stop includes

a bobbin-engaging portion and a rockshaft 56. (See Figs. 3 and 12). The end portions of the rockshaft extend through the side walls of the magazine, and one end of each rockshaft is provided with an arm 57. 70

The several arms 57 are arranged to coact respectively with detents 58 as shown best by Fig. 3. The function of each detent is to lock the stop 55 in position to support a stack of weft carriers. The detents 58 are 75 pivotally mounted upon pivot pins 59 on the side of the magazine. Each detent has a finger 60 arranged to be engaged and actuated by a tripping member 61. There is one such tripping member for each detent. The 80 several tripping members are arranged upon but not affixed to a rockshaft 62, said rockshaft being capable of turning under certain conditions, hereinafter explained, without moving any or all of the tripping members. The rockshaft is provided with a series of collars 63. These collars are pinned or otherwise affixed to the rockshaft so that they all turn in unison with the rockshaft. Helical torsion springs 64 are arranged to 85 transmit motion from the collars 63 to the tripping members 61, but if the tripping members are restrained, as will be explained in due course, when the rockshaft turns, such turning will result merely in deflection 90 of the springs. 95

The lowest weft carrier shown in Fig. 3 is resting upon the endless conveyer, its ends being in the sockets 50, 51 provided for that purpose. A spring plunger 65 is arranged to slide in a suitable bearing formed in the support 42, and its outer end is arranged to be engaged by the tripping member 61. This plunger is normally pressed toward the tripping member 61 by a helical compression spring 66. The inner or left-hand end of plunger 65 is arranged to abut against the weft carrier resting on the conveyer, and so long as there is a weft carrier in position to be engaged by the plunger the latter will prevent the tripping device 61 from retracting the detent 58 from the arm 57. There is one stop 55 for each stack of weft carriers, one detent 58 for each 100 stop, one tripping member 61 for each detent excepting that for the rear stack, and one restraining member 65 for each tripping member. The detent 58 for the rear stack of weft carriers is intended to be tripped manually when the magazine has 105 been placed in position upon the supports 42, 43, and the other detents are thereafter tripped automatically as will be explained. 110

As shown by Fig. 1 all the weft carriers have been discharged from the rear compartment of the magazine, and the weft carriers in all the other compartments are supported by their respective stops 55. So long as there is a weft carrier on the conveyer in vertical register with the second 115 120 125 130

compartment from the rear, the stop 55 in the second compartment will remain locked in supporting position; but when the rear weft carrier on the conveyer has passed beyond vertical register with the second compartment, the corresponding locking plunger 65 will be capable of longitudinal motion the next time the rockshaft 62 moves to operate the tripping members 61. When the rockshaft is actuated the rear tripping member 61 retracts the detent 58 by which the weft carriers in the second compartment are released. As the conveyer moves forward step by step, the weft carriers drop step by step and find their way successively into the sockets in the conveyer. The rockshaft 62 is operated once for each operation of the shuttle-loading mechanism, but the tripping members 61 are released one at a time only when their respective locking plungers 65 are left free by the weft carriers on the conveyer. The several stacks of weft carriers are thus released one after another in regular order, and the releasing operation in each case cannot occur until the last weft carrier of the preceding series has been carried beyond vertical register with the stack next in order for release.

The mechanism for operating the rockshaft 62 is shown by Figs. 1, 2 and 12. An operating arm 67 is affixed to the rockshaft and is pivotally connected with the upper end of a connecting rod 68, said upper end being bent, as shown by Fig. 1, to afford such connection. The lower end of the connecting rod is pivotally connected to a lever 69. The fulcrum member of this lever is indicated at 70. A cam 71 carried by a shaft 72 coacts with a roll 73 mounted on the lever. In the present instance lever 69 is used for the additional purpose of lifting the movable shuttle-box front 74 to release the shuttle x' when the shuttle-changing mechanism is brought into action. The member 74 is carried by a pair of arms such as that indicated at 75. These arms are affixed to a rockshaft 76. An arm 77 affixed to the rockshaft is pivotally connected to the upper end of a rod 78. The lower end of this rod is pivotally connected to the forward end of the lever 69. A helical tension spring 79 is connected to one of the arms 75 and normally keeps the roll 73 in contact with cam 71. Shaft 72 is commonly known as the change shaft in looms of the type shown, and operates only when a change of shuttles is necessary. When a shuttle-changing mechanism is brought into operation the change shaft describes one revolution and is then automatically stopped, and it is at such times that the connecting rod 68 is moved to turn rockshaft 62 to release a stack of weft carriers in the magazine, provided such release is in order.

The description up to this point is complete as to the magazine, the discharge of weft carriers from the magazine to the conveyer, the transfer of weft carriers from the magazine into register with the shuttle-loading mechanism, and the operation of the latter mechanism. It has been stated that mechanism is provided for detaching the weft-end carriers c from the bobbins successively as each weft carrier reaches the position indicated at a in Figs. 1 and 6. The mechanism for detaching the weft-end carriers is operated by the shuttle carrier 80 (Fig. 1) which interchanges the shuttles. This carrier is substantially the same as that shown in the aforesaid copending application, but a brief description of it will be necessary for present purposes. This carrier includes an oscillatory arm 81 mounted upon a fulcrum stud 82. A roll 83 carried by the arm coacts with a cam 84 on the change shaft 72. A helical tension spring 85 is connected to the arm and exerts its tension to move the carrier toward the lay in accordance with the contour of cam 84. The return motion of the carrier is effected positively by the cam. As shown by Fig. 1 the carrier is in its extreme forward position, to which it moves after depositing a spent shuttle on the support 15. The extra forward travel of the carrier after depositing a spent shuttle is utilized to set the detaching mechanism in position to get hold of a weft-end holder. For this purpose the carrier is provided with a member 86 which rides over and depresses a roll 87. This roll is mounted upon an arm 88, and the said arm is affixed to a rockshaft 89. A bevel gear 90 affixed to shaft 89 coacts with a bevel gear 91 fastened to shaft 92. Referring to Figs. 2, 9 and 10, an arm 93 is affixed to the upper end of shaft 92 and has pin-and-slot connection with an arm 94. In the present instance the pin is carried by arm 93 and is indicated at 95, and the slot is formed in arm 94 and is indicated at 96. The fulcrum member of arm 94 is indicated at 97. The free end of arm 94 extends loosely through an opening formed in a slide 98. This slide is arranged to move back and forth on a rod 99. Any suitable provision may be made for preventing the slide from turning about the axis of rod 99, and for this purpose the rod is preferably made square in cross section, as shown best by Figs. 8 and 9. The slide is provided with an extension or finger 100, and the latter is arranged to engage the rim or flange c' of the weft-end carrier. When this device is in its initial position as shown by Figs. 2 and 10, the finger 100 stands between the weft-end carrier and the body of the bobbin. The shape of the finger 100 is shown best by Figs. 8 and 9. It is so shaped that

it will bear lapped relation to the weft-end carrier but will leave sufficient clearance for the bobbin.

- The operation of this mechanism is as follows. When the shuttle carrier 80 is forward, as shown by Fig. 1, the stripper 100 occupies the position shown by Figs. 2 and 10. Upon operation of the shuttle-changing mechanism the shuttle carrier moves to the rear, thus releasing the roll 87. A helical torsion spring 89' (Fig. 10) is thus permitted to turn rockshaft 89 to impart stripping motion to the stripper as indicated by arrows on slide 98 in Figs. 2 and 10. The detachable member *c* of the weft carrier which is then in register with the shuttle-loading mechanism is thus stripped from the smaller end of the bobbin, and drops into a trough 101. The travel of the slide 98 is sufficient to carry the member *c* beyond the outer end of the trough, and the member *c* is consequently discharged from the trough and may drop into a suitable receptacle (not shown).
- Inasmuch as the weft end is fastened to the weft-end carrier when the latter is discharged, a few convolutions of the weft are unwound from the bobbin and are drawn through a slot 102 formed in the bottom of the trough 101. The outer end of the shuttle support 15 is provided with an upstanding wall 15' whereby the spent shuttle is registered relatively to the loading mechanism. This wall 15' is provided with a slot 103 the upper end of which registers with the aforesaid slot in the trough 101. (See Figs. 8 and 9). The stretch *b* of weft running from the bobbin to the weft-end carrier is thus drawn into the slot 102 and held therein by the discharged weft-end carrier. The weft-end carrier draws the weft end to the lower end of the slot 103, and the weft end is thus caused to bear upon the shuttle as shown by solid line in Fig. 13. When the loaded shuttle is carried by carrier 80 from the support 15 to the shuttle box of the lay, the stretch *b* of weft running from the shuttle to the slot 103 of the shuttle support moves across the outer end of the shuttle and is drawn laterally into the throat *x²* of the shuttle as indicated by dotted lines in Fig. 13. The shuttle is thus threaded while on its way to the shuttle box of the lay.
- An arm 104 is affixed to rockshaft 89 and is arranged to confine the shuttle in bobbin-receiving position on the support 15'. The arm 104 drops when the shuttle carrier 80 moves to take up the loaded shuttle, and remains below the path traversed by the shuttle during the interchanging operation until the carrier 80, after having deposited the spent shuttle on the support 15, engages and depresses the roll 87. The stripper remains in its outer position during the inter-change of shuttle but is returned to its in-

itial position when the shuttle-carrier depresses roll 87.

During the operation of the shuttle-changing mechanism a cam 105 on the change shaft 72 lifts a lever 106 to prepare the loading mechanism for operation. This lever lifts a rod 107 which in turn lifts the bar 23 into register with the striker 24. A pivoted latch 108 catches a pin 109 on the bar to hold the latter in register after the rod 107 drops.

Upon the completion of the cycle of the shuttle-changing mechanism the change shaft stops and the weaving mechanism of the loom starts in consequence of automatic controlling means (not shown) as in the Stafford loom. It is to be noted that the bobbin at *a* has had its weft-end holder *c* removed, and that the stripper 100 has been returned to its initial position. Consequently upon the first beating-up stroke of the lay the bobbin at *a* is ready to be driven into the spent shuttle, and upon the next step of the rotary carrier 25 the stripper 100 is in position to register with the next bobbin which replaces that at *a*. The pin 109 of the bar 23 is disengaged from the latch 108 by the forward movement of the bar, and the latter drops during the first traverse of the lay to the rear.

I claim:

1. The combination with shuttle-loading mechanism, of a bobbin magazine adapted to hold full bobbins, a series of movable bobbin carriers each adapted to carry a full bobbin, means arranged to move said carriers to carry a series of full bobbins from said magazine, and means arranged to transfer such bobbins from said bobbin carriers successively into register with said shuttle-loading mechanism.

2. The combination with shuttle-loading mechanism, of a bobbin magazine adapted to hold full bobbins, an endless conveyer having bobbin holders adapted to hold full bobbins, means arranged to drive said conveyer to carry a series of bobbins from said magazine, and means arranged to transfer such bobbins from said bobbin-holders successively into register with said shuttle-loading mechanism.

3. The combination with shuttle-loading mechanism, of a bobbin magazine adapted to hold full bobbins, and endless conveyer and means arranged to drive the latter to carry a series of full bobbins from said magazine, said conveyer having two series of sockets arranged to take the ends of the bobbins, and means arranged to transfer such bobbins from said conveyer successively into register with said shuttle-loading mechanism.

4. The combination with shuttle-loading mechanism, of an endless conveyer having a series of bobbin-carrying elements, a bob-

bin magazine arranged to discharge bobbins into said elements, means including a rotary carrier having a series of bobbin-receiving sockets arranged to transfer such bobbins from said conveyer successively into register with said shuttle-loading mechanism, and means arranged to drive said conveyer, said bobbin-carrying elements being arranged to place the bobbins in said sockets of said transferring means.

5 10. The combination with shuttle-loading mechanism, of bobbin-feeding means including a rotary carrier having a series of bobbin-receiving sockets arranged to carry bobbins successively into register with said mechanism, an endless conveyer having a series of bobbin-carrying devices, and means arranged to drive said conveyer, said bobbin-carrying devices being arranged to cause 15 the bobbins to gravitate successively into said sockets of said bobbin-feeding means.

15 20. 6. The combination with shuttle-loading mechanism, of an endless conveyer having a series of bobbin-carrying devices, means arranged to drive said conveyer, and bobbin-feeding means including a carrier having bobbin-engaging elements arranged to straddle the bobbins, said bobbin-carrying devices being arranged to place the bobbins 25 between pairs of said bobbin-engaging elements, said bobbin-feeding means being arranged to transfer the bobbins from said conveyer into register successively with said shuttle-loading mechanism.

25 30. 7. The combination with shuttle-loading mechanism, of an endless conveyer having a series of bobbin-carrying devices, means arranged to drive said conveyer, and transferring means having a series of bobbin-engaging elements arranged to straddle the bobbins and move the latter successively into register with said shuttle-loading mechanism, said bobbin-carrying devices of said conveyer being arranged to place the bobbins successively between pairs of said bobbin-engaging elements.

35 40. 8. The combination with shuttle-loading mechanism, of bobbin-feeding means including a rotary carrier having a series of bobbin-receiving sockets arranged to move bobbins successively into register with said shuttle-loading mechanism, a bobbin-conveyer having pairs of sockets arranged to receive the ends of the bobbins, and means arranged to drive said conveyer, said sockets of said conveyer being arranged to discharge the bobbins successively in said sockets of said rotary carrier.

45 50. 9. The combination with shuttle-loading mechanism, of bobbin-feeding means including a rotary carrier having a series of bobbin-receiving sockets arranged to move bobbins successively into register with said shuttle-loading mechanism, an endless conveyer having a series of bobbin-receiving

55 sockets, and means arranged to drive said conveyer, said sockets of said conveyer being arranged to carry the bobbins successively into said sockets of said rotary carrier. 70

10. The combination with shuttle-loading mechanism, of a bobbin magazine, a carrier arranged to carry a bobbin from said magazine, and transferring means including a movable bobbin-engaging device having bobbin-receiving sockets, said transferring device being arranged to transfer a bobbin from said carrier into register with said shuttle-loading mechanism, said carrier being arranged to carry a bobbin into said 75 sockets of said transferring device.

11. The combination with shuttle-loading mechanism, of a bobbin magazine, a carrier having companion sockets arranged to take the ends of a bobbin to carry the latter 80 from said magazine, and transferring means including a movable bobbin-engaging device having companion sockets arranged to receive the bobbin, said carrier being arranged to carry the bobbin into said sockets 85 of said transferring device, said transferring device being arranged to move the bobbin into register with said shuttle-loading mechanism.

12. The combination with shuttle-loading mechanism of a rotary device having a series of bobbin-receiving sockets, means arranged to drive said device step by step to move the bobbins into register successively with said shuttle-loading mechanism, an 95 endless conveyer having a series of bobbin-holding devices, and means arranged to transmit motion from said rotary device to drive said conveyer, said conveyer being arranged to deposit bobbins successively in 100 said sockets of said rotary device.

13. The combination with shuttle-loading mechanism, of a magazine for weft-carriers, means arranged to transfer weft-carriers from said magazine to registration successively with said shuttle-loading mechanism, said magazine having a plurality of chutes each adapted to hold a series of weft-carriers one upon another, said chutes being arranged to discharge the weft-carriers upon 110 said transferring means, a stop arranged to move to and from the path of the weft-carriers in one of said chutes, a detent arranged to hold said stop in said path, a tripping device arranged to trip said detent to release 115 said stop, trip-operating means arranged to act periodically on said tripping device to operate the latter, and restraining means arranged to abut against a weft-carrier on said transferring means to restrain said tripping device, said trip-operating means having a yielding element arranged to yield to the restraining coaction of said restraining means and a weft carrier. 120

14. The combination with shuttle-loading 125

mechanism of a bobbin magazine comprising a series of compartments each constructed and arranged to hold a series of full bobbins stacked one upon another, mechanism for 5 transferring the bobbins from said magazine to said loading mechanism, said transferring mechanism including a flexible endless conveyer arranged to pass under said compartments, the latter being constructed and 10 arranged to discharge the bobbins directly to said conveyer, bobbin-detents associated with said compartments respectively, and mechanism for operating said detents successively to release the bobbins, the latter 15 said mechanism being controlled as to each detent by a bobbin on said conveyer.

15. The combination with shuttle-loading mechanism of a bobbin magazine comprising a series of compartments each constructed and arranged to hold a series of full bobbins stacked one upon another, mechanism for transferring the bobbins from said magazine to said loading mechanism, said transferring mechanism including a flexible endless conveyer arranged to pass under said compartments, and having 20 sockets for holding the bobbins by both ends, said compartments being arranged to discharge the bobbins directly to said conveyer so that the ends of the bobbins will 25 enter said sockets.

16. The combination with shuttle-loading mechanism, of a bobbin magazine having a series of compartments each constructed and arranged to hold a series of full bobbins stacked one upon another, and mechanism for transferring the full bobbins from the magazine to the shuttle-loading mechanism, said transferring mechanism including a

flexible endless conveyer arranged to pass 40 under each of said compartments, the latter being constructed and arranged to discharge the bobbins by gravitation directly to said conveyer.

17. The combination with shuttle-loading mechanism, of a bobbin magazine having a series of compartments each constructed and arranged to hold a series of full bobbins stacked one upon another, mechanism for transferring the full bobbins from the magazine to the shuttle-loading mechanism, said transferring mechanism including a flexible endless conveyer arranged to pass under each of said compartments, the latter being constructed and arranged to discharge the bobbins by gravitation directly to said conveyer, and mechanism for controlling the discharge of bobbins from said compartments successively so that only one compartment at a time can discharge. 45 50 55 60

18. The combination with shuttle-loading mechanism, of mechanism for feeding a series of bobbins thereto, said feeding mechanism including a flexible endless conveyer having a straight upper stretch and having 65 sockets to hold the bobbins by both ends, a bobbin-magazine comprising a series of compartments each constructed and arranged to hold a series of bobbins stacked one upon another, said compartments being arranged 70 to discharge the bobbins by gravitation directly to said sockets in said straight upper stretch, and means for driving said conveyer step by step to register said sockets successively with said compartments. 75

In testimony whereof I have affixed my signature.

WILLIAM L. BARRELL.
